UNITED STATES PATENT OFFICE.

RICHARD JACKSON AND LEONARD O. SMITH, OF PHILADELPHIA, PA.

IMPROVEMENT IN SEWING-MACHINE FAN ATTACHMENTS.

Specification forming part of Letters Patent No. 151,224, dated May 26, 1874; application filed April 21, 1874.

To all whom it may concern:

Be it known that we, RICHARD JACKSON and LEONARD O. SMITH, both of Philadelphia, in the county of Philadelphia and State of Pennsylvania, have invented certain new and useful Improvements in Fans for Sewing-Machines; and we do hereby declare the following to be a full, clear, and exact description of the invention, such as will enable others skilled in the art to which it pertains to make and use it, reference being had to the accompanying drawings, which form part of this specification, in which—

Figure 1 is a side elevation of our improvements applied to a sewing-machine. Fig. 2 is a front view of a presser-bar with rod attached. Figs. 3, 4, and 5 are views of modifications.

The object of our invention is to provide an improved combination of devices for attaching a fan to a sewing-machine, whereby the motion of the fan will be similar to that ordinarily produced by hand, the stroke or sweep being also regulated and controlled. The nature of our invention consists in the peculiar combination and construction of parts, as hereinafter fully described.

In carrying our invention into effect we affix to the face of the machine, by means of a clamp, a stationary arm whose remote end is provided with a joint to which the handle of an ordinary fan is secured by another clamp. The lower section of this latter clamp is extended to form a rod on which fits a sleeve having a jointed connection with a rod that is attached to the needle-bar of the machine. When the needle-bar moves up and down the attached rod has a vertical motion communicated to it, which gives a corresponding vibratory motion to the fan-clamp rod and fan. The connecting-link may be slid on the needle-bar rod to adjust the stroke or sweep of the fan, accordingly as it is secured nearer to, or farther from, the pivot on which the fan vibrates.

Referring to the accompanying drawing, A represents the face of a sewing-machine, and B the needle-bar thereof, having a vertical motion in said face A. D represents a stationary arm, braced, if desired, as shown at d, and secured, by a clamp, C, to the face A.

The remote end of the stationary arm D is bent to form a vertical standard, E, to the upper extremity of which is secured a jointed clamp, F, for holding the fan L. This clamp F is made in two sections, f and f', the latter being extended, as shown, to form a rod. G is a rod secured to the needle-bar by any suitable means, preferably by a clamp which embraces the acorn by which the needle-bar is usually surmounted. This rod G should be bent, as shown, to clear the presser-bar of the machine. H represents a joint or standard, whose lower extremity is a slide by which it may be moved along the rod G for purposes of adjustment, its upper end being jointed to the sleeve I. Both the sleeve and slide may be fastened on their respective rods by a setscrew.

A modification of the foregoing construction is shown in Fig. 3, wherein, instead of the rigid standard E, having a joint at its upper extremity, we use a spring, K, which may be set to exert its returning power on the fan L either upwardly or downwardly, as may be desired.

Another modification is shown in Fig. 4, wherein the bar G is fulcrumed at g.

This invention is designed principally for that class of machines adapted to manufacturing purposes, being those generally in which a needle-bar is employed. It may, however, with a slight modification within the spirit of the invention, be adapted to what are ordinarily known as domestic sewing-machines, or those in which a needle-arm, having a vibrating motion, as distinguished from a needle-bar having a direct vertical motion, is employed.

What we claim as our invention is—

1. The horizontal stationary arm or fan-support D, secured to the face or stationary part of the machine, and terminating at its outer extremity in a joint or spring on which the fan works up and down, when combined and arranged substantially as shown and specified.

2. The elongated rod f', running from the fan-clamp, and the connecting-joint H, by the sliding of which the sweep or stroke of the fan may be regulated.

3. The combination of the rod G, attached to the needle-bar or needle-arm, with the connecting sliding joint, substantially in the manner and for the purpose herein set forth.

4. The combination of the stationary arm D, terminating in a joint or spring, the rods f' and G, and the connecting-link H, substantially as shown and described.

In testimony that we claim the foregoing we have hereunto set our hands this 18th day of April, 1874.

RICHARD JACKSON.
LEONARD O. SMITH.
